(57) **CLAIM**

The ornamental design for a stimulation device, as shown and described.

DESCRIPTION

FIG. 1 is a front perspective view of a stimulation device showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is the top plan view thereof; and,

FIG. 7 is the bottom plan view thereof.

The broken lines in the drawings depict portions of the stimulation device that form no part of the claimed design. In particular, the controls, the on/off button, and the plurality of air channels form no part of the claimed design.
